NECKTIE

James Fallar, Kitchener, Ontario, Canada, assignor to Cluett, Peabody & Co., Inc., Troy, N. Y., a corporation of New York

Application February 11, 1933. Serial No. 656,267

2 Claims. (Cl. 40—2)

In the manufacture of neckties, particularly of the better class, it is customary to affix a permanent label showing any one or more of a number of facts relating to the origin and character 5 of the product, such as the manufacturer's name and/or trade mark, the character of the material used in making the necktie, that the material is imported, the name of the retailer for whom the product is manufactured, etc.; and where several 10 of these items are included the label must be so large as to be unduly conspicuous when exposed. Ordinarily the label is sewed around its entire periphery to the rear side of the larger end of the tie, and inasmuch as most neckties are made 15 in tubular form, usually by folding the lateral margins into overlapping relation at the back, the label is applied over the "right" side of the material, thus making the patch-like appearance of the label even more conspicuous. This mode of 20 application also requires the additional operation of sewing the label to the tie and, when stitched along all four edges as heretofore customary, this additional operation adds materially to the cost of production.

According to the present invention the label is applied to the rear of the tie so as not to be visible from the front but instead of being applied over the right side of the material at the back it is applied to the lower edge of the back, which 30 is shorter than the front, so as to project over the rear face of the projecting front. Thus instead of appearing as a patch over the right side of the material it appears as a tab projecting over the wrong side of the front portion of the tie. The label may be affixed by the same row of stitching which secures the turned margin of the lower end of the back of the tie, thereby requiring no more stitching than is required to make a tie without a label. The label is preferably folded 40 with the folded ends stitched to the tie as aforesaid so that the free end of the projecting tab comprises a fold instead of a raw edge and so that indicia may be applied to both sides of the label, thereby displaying twice as much indicia 45 for a given size label. The end edges of the label are preferably made V-shaped with their apexes substantially at the fold line and the portions of the edges on each side of the fold line approximately parallel, so that when the label is folded 50 the two portions of each V-shaped edge are brought together and are oblique to the edges which are to be stitched to the end of the necktie. By making the inclination of these V-shaped 55 ends equal to the slope of the lower end of the back of the necktie and stitching the folded edges

of the label parallel with the end of the tie, the tab label projects parallel with the longitudinal dimension of the tie and hangs vertically when the tie is held in normal position. The labels are preferably made in the form of a strip which 60 when cut along V-shaped lines, at intervals equal to the length of a label, form individual labels having selvage edges to be folded together and having the end edges oblique to the longitudinal and transverse dimensions of the fabric so as 65 not to ravel. The indicia is arranged on one or both sides of the center line of the strip in such manner as to accommodate said V-shaped cuts.

For the purpose of illustration typical embodiments are shown in the accompanying drawing 70 in which,

Fig. 1 is a rear elevation of the lower end of one style of necktie;

Fig. 2 is a plan view of a strip of labels for use with the style of necktie shown in Fig. 1; 75

Fig. 3 is a plan view of an individual label of the same type;

Fig. 4 is a section on line 4—4 of Fig. 1;

Fig. 5 is a view similar to Fig. 1 showing another style of necktie; and 80

Fig. 6 is a plan view of a strip of labels for use with the style of tie shown in Fig. 5.

In the style of necktie shown in Fig. 1 the back is formed of two folds 1 and 2, the second fold being wider than the first and being stitched over the first fold as shown at 3. The lower end of the tie is cut obliquely with the back portions 1 and 2 shorter than the front portion to expose an area 4 of the rear side of the front portion. The label 5 is shaped as shown in Fig. 3 and is folded about the center line 6 to bring the edges 7 and 8 together. These edges are stitched to the lower oblique end of the fold 2 by the same row of stitching 9 which secures the inturned end 10 of the fold 2 to the back of the fold. By 85 making the inclination of the V-shaped ends (Fig. 3) of the label equal to the slope of the lower end of the back fold 2 of the necktie, the tab label projects from the lower end of the necktie parallel with the longitudinal dimension 90 of the tie. When the label is attached in this manner the indicia on one side of the fold line is normally visible at the back of the tie and the indicia on the other side of the fold line may be 100 inspected by swinging the tab upwardly away from the area 4.

The necktie shown in Fig. 5 is like that shown in Fig. 1 except that the wide fold 2' is on the left-hand side of the narrow fold 1', the tab 5' 110

being constructed like the tab 5 except in that it is reversed end to end.

Labels for use with the style of necktie shown in Fig. 1 are preferably woven in elongate strips 5 such as shown in Fig. 2, the indicia being arranged so that the individual labels may be cut off along the V-shaped lines 11. With the threads of the woven strip running longitudinally and transversely of the strip in the customary way, 10 the straight edges 7 and 8 are selvage edges and the V-shaped edges extend obliquely to the directions of the threads so as not to ravel. In forming labels for the style of the tie shown in Fig. 5 the procedure is the same except in that the indicia is so arranged that the spaces for the V-shaped cuts 11 incline in the opposite direction lengthwise of the strip.

It should be understood that the present disclosure is for the purpose of illustration only and 20 that this invention includes all modifications and equivalents which fall within the scope of the appended claims.

I claim:

1. A label for attachment to the oblique end of

25

a necktie after being folded along a medial line to bring opposite edges together, characterized in that the other pair of opposite edges are V-shaped with their apexes substantially at said fold line and the portions of the edges on each side of the fold line approximately parallel, so that when the label is folded the two portions of each V-shaped edge are brought together and are oblique to said first edges.

80

2. In combination with a necktie of the tubular type having the rear portion shorter than the front portion so that the front portion is visible from the rear throughout a substantial area beyond the end of the rear portion, a label folded at one edge and having its opposite edges secured to said end, the label having indicia on its outer faces at each side of the fold, said end being oblique to the longitudinal dimension of the necktie and the opposite sides of the projecting part of the folded label being approximately parallel with said dimension and the folded edge of the label being approximately parallel with said oblique end of the necktie.

JAMES FALLAR.
